UNITED STATES PATENT OFFICE.

AUGUST E. VOGLER, OF HOBOKEN, NEW JERSEY, AND CHARLES G. RICHARDSON, OF NEW BRIGHTON, NEW YORK.

GAS-BURNER.

SPECIFICATION forming part of Letters Patent No. 593,342, dated November 9, 1897.

Application filed April 20, 1897. Serial No. 633,058. (No model.)

To all whom it may concern:

Be it known that we, AUGUST E. VOGLER, a subject of the Emperor of Germany, and a resident of Hoboken, Hudson county, State of New Jersey, and CHARLES G. RICHARDSON, a subject of the Queen of Great Britain and Ireland, and a resident of New Brighton, Richmond county, State of New York, have invented certain new and useful Improvements in Gas-Burners, of which the following is a specification.

Our invention relates to improvements in gas-burners, especially such as are adapted for use with incandescent mantles.

15 The purpose of the invention is to provide simple and efficient means for producing thorough admixture of air and gas in the proper proportions for perfect combustion, so as to prevent the deposit of unconsumed carbon upon the mantle and secure the best heating and illuminating effects from the flame.

Referring to the drawings which accompany the specification to aid the description, Figure 1 is a vertical section of our burner and showing a chimney and mantle in position. Fig. 2 is an elevation of the same. Fig. 3 is a cross-section on the line 3 3 of Fig. 1. Fig. 4 is a detail showing the preferred mode of retaining the rod which supports the mantle in position.

A is a shell or case of sheet metal and preferably of globular form, as shown, to give a large area for the gas and air to mix in around the tip B, which is threaded into the threaded 35 inturned sleeve a of said shell A. Said tip B is also internally threaded for a gas connection and is provided with the usual perforated diaphragm b'. Said shell A is provided with an open-top sheet-metal sleeve C, secured to the said shell by being pressed partly around the head b, as shown, or said 40 sleeve C may be formed integral with said shell A, and d is a slot in said sleeve for the passage of the transverse shaft E, provided 45 with long pinion-teeth e for operating the tube F, which regulates the air-supply, as will be hereinafter described. The sleeve g of the chimney-gallery G fits on said sleeve C and is perforated at h to admit air to the said shell 50 A, H being the usual ring for supporting a globe if one is used. The combined mixing-

chamber and burner-head J, of sheet metal, fits in said sleeve g, being shouldered, as at j, to properly position it in said sleeve. A short distance below the top of sleeve g said 55 burner-head turns rather abruptly inward, as at k, and thence descends as a neck or sleeve l nearly to the bottom of the aforesaid sleeve c. Said neck l constitutes a guide-sheath for the aforesaid regulating-tube F, which is provided in one side with rack-teeth m, which mesh with the pinion-teeth e of shaft E. Said tube F may either be arranged inside sleeve l, as shown, or outside said sleeve, it only being necessary that it should be capable of 60 motion toward and from the tip B. Said shaft E is positioned by a transverse sleeve n, carried by the sleeve g of the chimney-gallery. To facilitate assembling the parts, said shaft E, with its teeth e, and also the sleeve n are 65 made slightly tapering, as shown, and said shaft E may be provided with a suitable pin or shoulder e' to prevent longitudinal displacement, if desired. The rack-teeth on the regulating-tube F do not extend quite to the 70 ends of said tube, so that the play of the tube is limited, and the turning of the shaft E cannot entirely displace said tube.

A finely-perforated diaphragm p, such as wire mesh, is placed in the burner-head J just 75 above where it narrows, as shown. Said diaphragm p increases the effective mixing of the air and gas and also prevents the flame from working back to the gas-supply pipe. A ring O, of some non-conducting material, as soap-stone, provided with reduced upper and lower edges which fit snugly into the upper end of said burner-head J and into the lower end of the cap R, insulates said cap from and keeps the lower parts of the device cool. Said cap 80 R constitutes the top of the burner proper and is perforated with radial slits r, through which the mixed gas and air escape to the flame. Said cap R may be provided, if desired, with a dependent socket s for the lower 85 end of the rod which supports a mantle S, but we prefer to carry the mantle-supporting rod T down outside the mantle and fasten its end in a hole in a block u, carried on the chimney-gallery G, by a set-screw v, W being any usual 90 chimney.

In use the operator turns the shaft E by a

- key E', which fits the square end of said shaft, and thereby moves the regulating-tube F upward from the tip B to increase the amount of air admitted to the shell A or downward 5 toward said tip B to decrease the amount of air admitted, and we find that this mode of regulation, in connection with the enlarged area of the combined burner-head and mixing-chamber J, secures a very perfect mixing of 10 the gas and air, so that a shorter mixing-chamber can be used than is now required, and a shorter chimney suffices to produce the requisite incandescence of the mantle. The efficient operation of the device is also promoted by the fact that the air becomes considerably heated as it descends the chimney and the sleeve c on its way to the point where it mixes with the gas, thus producing a regenerative effect.
- 20 Referring to Fig. 4, the rod T is clamped in position by the spring X, which is formed of a single piece of elastic metal and with two leaves x x', as shown. Said spring is soldered to the sleeve g of the chimney-gallery. There 25 is a hole y in the upper leaf in line with a hole z, which is formed in a suitable projecting part of the gallery. A slot y' in the lower leaf x' of said spring X is normally out of line with said holes y z, so as to clamp and 30 hold the rod when in place in said holes. To release the rod, the user presses the lower leaf upward to the position of the dotted lines, thereby bringing slot y' into line with holes y z and freeing said rod.
- 35 Now, having described our improvements, we claim as our invention—
1. The combination with the shell A burner-tip B and burner-head J, of the vertically-adjustable tube F movable in said shell A 40 and adapted to seat on said tip B and constitute a valve for regulating the air-supply, rack-teeth thereon, and a pinion engaging said teeth, substantially as described.
  2. The combination of a shell provided with 45 a burner-tip connecting with a gas-supply

pipe, air-inlets communicating with the upper part of said shell, a regulating-tube movable in said shell and adapted to seat on said burner-tip, and constitute an air-regulating valve in said shell, a pinion for reciprocating said tube, a combined burner-head and mixing-chamber communicating with said regulating-tube, a diaphragm in said head, and outlets for mixed gas and air in said burner-head, substantially as described. 50

3. The combination of a shell provided with a burner-tip connecting with a gas-supply pipe, air-inlets communicating with the upper part of said shell, a regulating-tube movable in said shell and adapted to seat on said 60 burner-tip and constitute an air-regulating valve in said shell, a pinion for reciprocating said regulating-tube, a combined burner-head and mixing-chamber communicating with said regulating-tube, outlets for mixed 65 air and gas in said burner-head, a mantle-supporting rod, a socket, and a set-screw for said rod outside the burner-head, substantially as described.

4. The combination of a shell A provided 70 with a burner-tip B connecting with a gas-supply pipe and with inlets for air, a regulating-tube movable in said shell A and adapted to seat on said burner-tip B and constitute an air-regulating valve, a pinion for reciprocating said tube, a combined mixing-chamber and burner-head communicating with said tube, an insulating-ring in the wall of said burner-head, and a cap on said ring provided with outlets for mixed gas and air, substantially as described. 75

In testimony that we claim the foregoing as our invention we have signed our names, in presence of two witnesses, this 31st day of March, 1897.

AUGUST E. VOGLER.

CHARLES G. RICHARDSON.
